UNITED STATES PATENT OFFICE.

JOHN RIEGEL, OF EAST MAUCH CHUNK, PENNSYLVANIA.

HEATER.

1,263,702.

Specification of Letters Patent. Patented Apr. 23, 1918.

Application filed December 19, 1916. Serial No. 137,768.

To all whom it may concern:

Be it known that I, JOHN RIEGEL, a citizen of the United States, and a resident of East Mauch Chunk, in the county of Carbon 5 and State of Pennsylvania, have invented a new and Improved Heater, of which the following is a full, clear, and exact description.

The invention relates to steam and hot 10 water heaters, and its object is to provide a new and improved heater more especially designed for use in dwellings to furnish steam or hot water to radiators for heating purposes and arranged to enable the user to 15 heat the rooms more or less according to the seasons, that is, to give the rooms less heat during the fall and spring and more during the winter. Another object is to 20 utilize the fuel in an exceedingly economical manner and to permit burning of solid fuel such as coal, wood and the like, or gaseous fuel, or both at the same time, if desired.

In order to accomplish the desired result, 25 use is made of two boilers, of which one is the delivery boiler for delivering steam or hot water to the radiators for heating the rooms, and the other is a feed water heater connected with the said delivery boiler to 30 supply the latter with heated water, the said second boiler receiving the return water from the radiators supplied by the said delivery boiler. Use is also made of a specially constructed furnace on which the boilers are 35 mounted, the furnace having a combustion chamber for directly heating the delivery boiler by the products of combustion arising from the burning fuel of the combustion chamber, the products of combustion after 40 leaving the delivery boiler being utilized for heating the second or feed water boiler.

A practical embodiment of the invention is represented in the accompanying drawings forming a part of this specification, in 45 which similar characters of reference indicate corresponding parts in all the views.

Figure 1 is a sectional side elevation of the heater on the line 1—1 of Fig. 2;

Fig. 2 is a front end elevation of the same 50 with parts shown in section;

Fig. 3 is a cross section of the same on the line 3—3 of Fig. 1;

Fig. 4 is a sectional plan view of the same 55 on the line 4—4 of Fig. 2, and

Figs. 5, 6, 7, and 8 are views corresponding respectively to Figs. 1, 2, 3, and 4, show-

ing slight modifications in the application of my invention to hot water heating systems.

On the top of a specially constructed furnace 10 are mounted two boilers 11 and 12, of which the boiler 11 is preferably made in sections one in front of the other, and this boiler forms the delivery boiler for delivering steam or hot water to the radiators to 60 be supplied. The other boiler 12 is the feed water boiler or heater and is connected at its front end by a pipe 13 with the delivery boiler 11 to supply the latter with heated water. The tops of the sections of the delivery boiler 11 are provided with pipes 14 connected with a delivery pipe 15 leading to the radiators in connection with steam heating systems as in Figs. 1 to 4 inclusive, and the said second boiler 12 is also provided with an outlet pipe 16 connected with the delivery pipe 15 so that any steam that may be generated in this boiler 12 can pass into the delivery pipe 15 and to the radiators. 65 A return pipe 17 is connected with the feed water boiler 12 so that the return water from the radiators passes into the boiler 12 to receive a preliminary heating and to then pass by way of the pipe 13 into the delivery boiler 11. In connection with hot water 70 systems, a hot water outlet pipe 14^a leads from the rear section of the delivery boiler 11, and a cold water return pipe 17^a connects to the top of the feed water boiler 12, 75 all as seen in Figs. 5 to 8 inclusive.

The furnace 10 is provided with a main combustion chamber 20 having a grate 21 below which is arranged an ash pit 22, and suitable doors 23 and 24 are provided on the front of the furnace 10 and leading to the 80 combustion chamber 20 and the ash pit 22, respectively. The combustion chamber 20 is provided at its rear with an outlet 25 leading to the rear end of the delivery boiler 11 provided with the usual smoke flues 26 for the passage of the products of combustion 85 arising from the burning fuel in the fire box 20 and passing up the outlet 25. The front ends of the boilers 11 and 12 are connected with each other by a heading 27 to receive 90 the products of combustion from the front ends of the flues 26 and direct the said products of combustion to the front ends of the flues 28 in the other boiler 12. The products of combustion travel rearward through 95 the flues 28 and finally pass into a chamber 29 arranged in the rear end of the furnace 100 110

10 and connected with the chimney flue 30. From the foregoing it will be seen that by the arrangement described the products of combustion arising from the burning fuel in the fire box 20 first pass through the flues 26 of the boiler 11 to highly heat the latter and then the products of combustion pass through the flues 28 and finally to the chimney flue 30. Thus the products of combustion 10 are utilized to the fullest advantage to highly heat the delivery boiler 11 and to heat the boiler 12 sufficiently to heat the water therein for supplying the boiler 11 with heated water. It will be noticed that 15 if the heater is used as a steam heater, it is not necessary to provide an intense fire during the spring or fall as an ordinary fire is sufficient to generate steam in the boiler 11 while no steam is generated in the 20 other boiler 12. During the winter, however, a stronger fire is maintained in the fire box 20 so that steam is generated in both boilers 11 and 12.

A second combustion chamber 40 is arranged in the furnace 10 directly under the delivery boiler 11 and this combustion chamber 40 is provided with two burners 41 for burning gaseous fuel under the sections of the boiler 11 to heat either section or both simultaneously. The rear end of the said combustion chamber 40 is provided with an outlet 42 opening into the outlet 25 and controlled by a damper 43 having a handle 44 extending to the outside to enable the 30 user of the heater to close the opening 42 when the burner 41 is not in use and solid fuel is burned in the fire box 20. When, however, the burner 41 is used then the damper 43 is opened to allow the products 35 of combustion in the fire box 40 to pass through the outlet 42 into the outlet 25 and from the latter through the flues 26 to the header 27 and then through the flues 28 to the chamber 29 and the chimney flue 30. The 40 combustion chamber 40 is provided with suitable doors 45 for gaining access to the boiler 41 and for supplying air for combustion to the burning fuel.

It will be noticed that by the arrangement 50 described the delivery boiler 11 receives the heated water from the feed water boiler 12 and hence the level of the water in both boilers is always the same even when the delivery boiler only is heated sufficiently to 55 generate steam. Considering that both boilers are approximately alike in size half the amount of water evaporated in the boiler 11 is supplied from the boiler 12 and hence the level of the water in the boiler 11 60 does not fall a distance corresponding to the whole amount of water evaporated but only half the distance.

The delivery boiler 11 is preferably made in two sections so that in milder weather 65 only the first section, that is, the one next to

the outlet 25, is heated sufficiently to generate steam. Thus the user of the heater can readily regulate the generation of steam by burning more or less fuel according to the requirement in colder or milder weather. 70

The heater shown and described is very simple and durable in construction and can be cheaply manufactured, and, as above stated, either solid or gaseous fuel may be 75 used or both, if desired.

Having thus described my invention, I claim as new and desire to secure by Letters Patent:-

1. A heater, comprising two juxtaposed boilers of which one is the delivery boiler 80 and the other is a feed water heater connected with the said delivery boiler to supply the latter with heated water, the said second boiler receiving the return water from the radiators supplied by the said delivery boiler, the said boilers having parallel smoke flues extending from front to rear, and a furnace on which the boilers are mounted, the furnace having a combustion chamber connected with the rear end of the 85 said delivery boiler to conduct the products of combustion from the combustion chamber through the flues of the said delivery boiler, a connection at the front ends of the boilers to connect the products of combustion from the front end of the delivery boiler to the flues of the said second boiler and a horizontally disposed water connection between the lower portions of said boilers extending within said front connection 90 of the boilers.

2. A heater, comprising two interconnected and horizontally aligned boilers of which one is the delivery boiler and the other is a feed water heater connected with 105 the said delivery boiler to supply the latter with heated water, the said second boiler receiving the return water from the radiators supplied by the said delivery boiler, the said boilers having parallel smoke flues 110 extending from front to rear and a furnace on which the said boilers are mounted, the furnace having a combustion chamber provided with a grate, the rear end of the combustion chamber connecting with the rear ends of the flues of the delivery boiler, a front connection connecting the front ends of the boilers with each other to conduct the products of combustion from the front ends of the flues of the delivery boiler to the front 115 ends of the flues of the said second boiler, and a chimney flue connected with the rear end of the said second boiler.

3. A heater, comprising two boilers of which one is the delivery boiler and the 125 other is a feed water heater connected with the said delivery boiler to supply the latter with heated water, the said second boiler receiving the return water from the radiators supplied by the said delivery boiler, the said 130

boilers having smoke flues and a furnace on which the said boilers are mounted, the furnace having a combustion chamber provided with a grate, the rear end of the combustion chamber connecting with the rear ends of the flues of the delivery boiler, a front connection connecting the front ends of the boilers with each other to conduct the products of combustion from the front 5 ends of the flues of the delivery boiler to the front ends of the flues of the said second 10 boiler, a chimney flue connected with the rear end of the said second boiler, and a second combustion chamber directly under the said delivery boiler and provided with 15 a gas burner, the rear end of the said second combustion chamber being provided with a damper controlled outlet opening into the rear end of the said first-named combustion chamber.

JOHN RIEGEL.
